[57] **ABSTRACT**

A method of increasing the operating efficiency of a textile drafting machine such as a gilling machine wherein, instead of utilizing a large number of small, conventional size slivers from individual sliver cans, a single oversize sliver having a weight per unit length comparable to the collective weight per unit length of the many conventional size slivers and having a substantially higher tensile strength than the conventional size slivers is fed into the drafting zone of the drafting machine so that parting of the sliver is substantially eliminated. The invention also includes novel apparatus for accommodating a single large sliver can and the feeding of the single oversize sliver therefrom into the drafting machine.

METHOD FOR PROCESSING SLIVER

This application is a continuation-in-part of my copending application, Ser. No. 46,866, filed June 17, 1970, now abandoned and entitled **METHOD AND APPARATUS FOR PROCESSING COMBED TEXTILE SLIVERS**.

In the drafting of textile fibers through a drafting machine, for many years it has been the conventional practice to feed into the drafting machine a large number of conventional size slivers from a creel of individual sliver cans. In the case of processing worsted wool slivers, in particular, according to the French or Continental system, it has been the usual practice to feed 6 to 32 or more ends of worsted sliver, weighing in the range of $\frac{1}{8}$ to about 2 ounces per yard (about 55 to 875 grains per yard) from individual sliver cans into a gilling machine for straightening and parallelizing the fibers while drafting the same. Normally where the number of ends being fed into the gilling machines is on the high side of the aforementioned range of ends, the weight per yard for each end will be on the lower side of the range of weights and vice versa. It can be appreciated therefore that it has been necessary to utilize a large number of sliver cans to serve as the supply source for each drafting machine, and that a large number of supply cans of sliver had to be kept in reserve and at previous processing machines in order to replace empty cans with filled cans of sliver at the creels of the drafting machines. Such large numbers of sliver cans obviously require considerable floor space in the mill, notwithstanding the initial expense of obtaining such a large number of cans and the expense of maintaining such cans as well as the labor involved in moving them from place to place for storing the same and performing the usual doffing and donning operations.

Another problem which is quite critical attendant to the use of a plurality of individual conventional size slivers as the source of supply for a textile drafting machine is the fact that conventional size slivers are relatively weak and flimsy, since they are of light weight and have very little if any twist therein, and thus they become parted quite easily and with quite high frequency in their course from the usual small sliver cans into the drafting zones of textile drafting machines. Such frequent parting of the slivers being fed has resulted in considerable down time and consequent loss of production. In fact a conditioner gilling machine normally has operated heretofore at about 60 percent maximum efficiency. It follows that an attendant for a group of machines has been kept quite busy piecing-up the many individual conventional size slivers during the operation of the drafting machines, in addition to performing the usual doffing and donning operations and other duties necessary to the operation of the drafting machines.

It is therefore an object of this invention to provide an improved method of and apparatus for processing textile slivers and increasing the operating efficiency of textile drafting machines, especially gilling machines, while conserving floor space heretofore necessary for accommodating the many cans of conventional size sliver heretofore serving as a source of supply for each textile drafting machine, while substantially reducing the labor heretofore involved in the handling of the many cans of conventional size sliver, and substantially

eliminating parting of sliver being fed to each textile drafting machine.

It is another object of this invention to provide an improved apparatus facilitating the feeding of textile sliver into a textile drafting machine in such a manner as to eliminate the need for large creels such as have been required heretofore for accommodating the many cans of conventional size sliver heretofore serving as the source of supply for the textile machine.

It is a more specific object of this invention to provide a method of increasing the operating efficiency of a textile drafting machine having a drafting zone, such as a gilling machine, and conserving of floor space heretofore necessary for accommodating many cans of conventional size sliver heretofore serving as the source of supply for the textile machine, wherein the method comprises feeding into the drafting zone of the textile drafting machine only a single oversize sliver formed from a plurality of conventional size slivers and having a weight per unit length which is substantially equal to the collective weight per unit length of the many conventional size slivers required heretofore, and which single oversize sliver has a substantially higher tensile strength than the conventional size slivers so that parting of the sliver being fed is substantially eliminated.

It is another object of this invention to provide apparatus for the feeding into a drafting machine of only a single oversize sliver which apparatus comprises an unusually large, substantially cylindrical, castered sliver can, a locating device rearwardly of the machine and provided with a recess in its rear portion for matingly receiving a portion of the sliver can therein, and a downwardly and forwardly inclined conveyor whose rearmost portion is positioned above the sliver can adjacent the vertical axis thereof, and having its frontmost portion positioned adjacent the drafting zone of the drafting machine for feeding the oversize sliver into the machine.

Some of the objects of the invention having been stated, other objects will appear as the description proceeds, when taken in connection with the accompanying drawings, in which

FIG. 1 is a schematic plan view of a row of sliver forming textile machines with a coiler at one end thereof for coiling into a sliver can an oversize composite sliver composed of slivers from the row of machines, and also showing such a composite sliver being withdrawn from a sliver can and fed into a textile drafting machine;

FIG. 2 is an enlarged side elevation of the textile drafting machine, showing the same in the form of a gilling machine, and being taken substantially along line 2-2 in FIG. 1; and

FIG. 3 is a perspective view of the gilling machine of FIG. 2, but omitting the large sliver can.

Referring more specifically to the drawing, the numeral 10 indicates a row of sliver forming machines, such as drawing frames, gilling machines, combing machines, carding machines or the like, each of which receives textile fibers from a suitable source and forms the fibers into an individual conventional size sliver S. As schematically illustrated in FIG. 1, a creel 11 serves as a source of supply for each of the machines 10.

According to the method of the invention, instead of coiling the slivers from the machines 10 into respective sliver cans, as has been a widespread practice heretofore, the successive slivers S are directed from the sliver forming machines 10 onto a common moving conveyor means 12 and thereby combined in side-by-side substantially parallel relationship. During the combining of the conventional size slivers on the conveyor means 12, they are directed downstream to a package forming zone, in the course of which the slivers pass from the conveyor means 12 into and through a suitable coiler 13. Coiler 13 functions in a well known manner to condense the conventional size slivers into an oversize composite sliver S' (FIG. 2) without imparting draft to the same, and to coil the sliver downwardly into an unusually large sliver can 14 therebeneath constituting a composite sliver package.

It can be appreciated that the weight per unit length of the oversize composite sliver S' of the thus formed package is many times greater than that of each conventional size sliver S emerging from the sliver forming machines 10, and in actuality is substantially equal to the collective weight per unit length of all of the individual conventional size slivers thereof. In the processing of wool worsted fibers with which this invention is primarily concerned, each conventional size sliver S may weigh in the range of $\frac{1}{8}$ to about 2 ounces per yard, and anywhere from 6 to 32 conventional size slivers may be used in forming a desired composite sliver S', depending upon the stage of the processing thereof and the desired degree of blending. As shown in the drawings, 18 machines are arranged in a row for producing a corresponding number of slivers in forming the composite sliver S'.

It should be noted that, although the conventional size slivers S are combined to form the oversize sliver S', they are not drafted in their course from the sliver forming machines 10 to the large sliver can 14. Thus, the oversize composite sliver S' is composed of a plurality (six or more) conventional size slivers and has a weight per unit length substantially equal to the collective weight per unit length of all of the individual conventional slivers thereof. Also, it is apparent that the tensile strength of the oversize composite sliver is much greater than that of the individual conventional size slivers and, therefore, unintentional parting of the sliver in subsequent handling and through a subsequent drafting operation is substantially eliminated. Furthermore, by combining the many individual conventional size slivers into a single oversize composite sliver, it is apparent that this conserves floor space heretofore necessary for accommodating the many sliver cans heretofore serving as receptacles for the individual slivers emerging from the sliver forming machines 10.

Since the single sliver can 14 must accommodate the production of all of the sliver forming machines 10 whose slivers S are to be combined into the single oversize composite sliver S, it is preferred that the capacity of sliver can 14 is much greater than that of a single conventional size sliver can of about 12 to 14 inches diameter and about 32 inches high. Therefore, because of the greater capacity of sliver can 14 it is provided with casters 15 secured to the bottom wall thereof (FIG. 2) to facilitate moving the can 14 from place to place in the mill. Typically, sliver can 14 may be about

4 feet in diameter and about $5 \frac{1}{2}$ to 6 feet high. It is preferred that the substantially cylindrical body of sliver can 14 is made from a transparent or translucent material to enable the attendant to observe the amount of sliver therein without the need for looking into the open top of the can.

After sliver can 14 is filled with the desired amount of composite sliver S', it is doffed from coiler 13 and moved to a position adjacent the input end of a textile drafting machine or drawing frame shown in the form of a gilling machine 20. Gilling machine 20 includes a drafting zone 21 formed of driven feed rolls 22 and faster driven delivery drafting rolls 23 with upper and lower sets of intersecting fallers 24, 25 disposed between the feed and delivery rolls 22, 23. The gilling machine may be conventional to the extent just described and in that the small combed and drafted sliver S'' emerging from delivery rolls 23 may pass through a coiler head 27 to be coiled into a conventional size sliver can 30. Alternatively, in place of the coiler head 27 and can 30, gilling machine 20 may be equipped with a top balling device, not shown, but of well known construction, for traversing the sliver S'' onto a rotating spindle or bobbin. In any event, the single oversize composite sliver S' serves as the sole source of supply for the gilling machine 20.

To this end, conveyor means, comprising a driven endless conveyor belt 34, is positioned adjacent the input end of gilling machine 20. Conveyor belt 34 is mounted on rear and front rollers 35, 36. Since sliver can 14 is of substantially greater height than the drafting zone 21, the rear roller 35 is positioned substantially higher than front roller 36 so that the conveyor belt is inclined forwardly and downwardly from a position spaced above and adjacent the vertical axis of sliver can 14 to a position adjacent feed rolls 22. It should be noted in FIG. 2 that the angular position of the conveyor belt 34 forms an acute bight in the sliver S' passing thereover thus providing increased traction between the heavy sliver and the belt at this juncture.

Thus, conveyor belt 34 lifts and withdraws the composite sliver S' upwardly out of sliver can 14 along a path of travel coinciding substantially with the axis of the can to minimize dragging the sliver over convolutions thereof in the can during withdrawal of the sliver from the can. The conveyor belt then directs the thus lifted composite sliver downwardly and forwardly at an angle onto a conventional feed apron 37 and thence between feed rolls 22 of drafting zone 21. As shown, feed apron 37 is entrained over the lowermost of the feed rolls 22 and over an apron roll 40 connected by a drive mechanism 41 to the front conveyor roller 36 for driving conveyor belt 34 in timed relation to the rolls 22, 23 and fallers 24, 25 of drafting zone 21. It has been determined that the operating efficiency of gilling machines has been increased considerably by utilizing a single oversize sliver, as described, as the sole source of supply for each such machine. In fact, the gilling machine 20 operated at about 80 percent maximum efficiency as compared to a normal 60 percent maximum efficiency obtainable heretofore when a plurality of individual conventional size slivers from separate small sliver cans were used as the source of supply for the gilling machine 20.

Novel locating means 45 is provided for locating the unusually large sliver can 14 in the desired predetermined position rearwardly of gilling machine 20 and comprises an elevated platform 46 supported on legs 47. Platform 46 is provided with a substantially U-shaped opening 50 of such width and depth as to matingly receive the substantially cylindrical body of sliver can 14 therein. The bottom or front wall of opening 50 preferably is semicircular and is so positioned that the vertical axis of a can 14 positioned thereagainst will be substantially vertically aligned with the rearmost central portion of conveyor belt 34. Thus, the composite sliver S' is lifted upwardly from the central portion of sliver can 14 by conveyor belt 34.

Platform 46 may be about 12 to 18 inches high. Since the height of sliver can 14 may be about 5 1/2 to 6 feet, and the height of the upper portion of conveyor belt 34 may be up to about 9 feet above the floor in order for the rear upper portion of conveyor belt 34 to be located over the center of the sliver can 14, the locating means 45 is of stepped construction. Accordingly, a pair of relatively small auxiliary elevated platforms 52 may extend upwardly about 12 to 18 inches from the main platform 46 adjacent opposite sides of opening 50 and a sliver can positioned therein, so that an attendant may reach the sliver S' above the can by standing on either of the auxiliary platforms for piecing-up the sliver or performing other corrective work when needed.

It is thus seen that I have provided an improved method of and apparatus for processing sliver to increase the operating efficiency of a textile drafting machine and to conserve floor space required heretofore to accommodate many cans of conventional size sliver, wherein instead of feeding several individual conventional size slivers from separate sources or sliver cans into the drafting zone of the machine, a single oversize composite sliver formed from several conven-

tional size slivers serves as the sole source of supply for the drafting machine.

In the drawings and specification there has been set forth a preferred embodiment of the invention and although specific terms are employed, they are used in a generic and descriptive sense only, and not for purposes of limitation.

I claim:

1. A method of processing textile fibers which comprises feeding textile fibers through each of a plurality of sliver forming machines numbering about 18, with each sliver weighing at least 1/8 oz. per yard, while delivering the slivers as a separate conventional size sliver from each machine, while successively combining the conventional size slivers being delivered from the machines in generally parallel relationship on a common moving conveyor, while directing the conventional size slivers into and through a coiler to form a single oversize composite sliver therefrom having a weight per unit length substantially equal to the collective weight of all of the individual slivers thereof as they were delivered from the sliver forming machines, while coiling the composite sliver downwardly from the coiler into a large sliver can of about 4 feet in diameter and about 5 1/2 feet or more in height, transferring the sliver can with the composite sliver therein away from the coiler and to a position adjacent the input end of a textile drafting machine having a drafting zone, and then withdrawing the single oversize composite sliver upwardly out of the sliver can and feeding the composite sliver into the drafting zone as the sole source of supply for the drafting machine.

2. A method according to claim 1, wherein the step of withdrawing the composite sliver from the sliver can and feeding the same into the drafting zone comprises lifting the composite sliver upwardly out of the sliver can and onto a moving conveyor at the input end of the drafting machine.
